UNITED STATES PATENT OFFICE.

JOHN TWARDOWSKY, OF CHICAGO, ILLINOIS, ASSIGNOR, BY MESNE ASSIGNMENTS, TO UNIVERSE CORPORATION, OF CHICAGO, ILLINOIS, A CORPORATION OF ILLINOIS.

REFRIGERATOR-DOOR SEAL.

Application filed May 31, 1923. Serial No. 642,514.

To all whom it may concern:

Be it known that I, JOHN TWARDOWSKY, a citizen of Russia, residing at Chicago, in the county of Cook and State of Illinois, have 5 invented certain new and useful Improvements in a Refrigerator-Door Seal; and I do hereby declare the following to be a full, clear, and exact description of the invention, such as will enable others skilled in the art 10 to which it appertains to make and use the same.

My invention relates to means for sealing doors so as to afford a substantially air tight closure. Generally speaking, it aims to provide a simple and inexpensive arrangement 15 for this purpose and one which can readily be adjusted so as to provide the desired sealing effect regardless of variations in the exact size and interfitting of the door with 20 the door frame. Moreover, it aims to provide a seal of this class which can readily be adjusted from time to time if necessary, in which the sealing portion can readily be replaced if desired, and in which the seal is 25 effective both as to air and as to moisture.

In using refrigerators, it is well known that the required amount of cooling effect depends to a considerable extent on a tight closing of the refrigerating chamber with 30 respect to the outer air so as to prevent the outer (and much warmer) air from entering this chamber. If the cooling is effected by means of a mechanical refrigerating system in which power is derived from an electric 35 circuit, the cost of the current makes it all the more important that the required cooling action be reduced to a minimum, hence it is particularly desirable that the doors of mechanically cooled refrigerators should be 40 tightly sealed. Furthermore, since many kinds of fruits and vegetables, as well as other foods, are easily affected by the presence of moisture within the refrigerating chamber even if the latter is continuously 45 kept at a desirably low temperature, it is likewise important that the door of the refrigerating chamber should be kept tightly sealed so long as it is closed.

However, the usual refrigerator door constructions do not readily lend themselves to such a tight sealing, this being partly due to initial departures from an exact interfitting of the door with the frame and also 50 because these parts may gradually change 55 somewhat in their exact size and shape.

Such gradual changes have also spoilt the effectiveness of arrangements heretofore tried for this purpose whereby strips of rubber were interposed either flatwise or edge-wise between the door and the door frame to afford the desired seal. My present invention also employs an interposed sealing member, but provides a novel arrangement both for this sealing member and for the adjacent parts of the refrigerator, so that 60 the sealing member can automatically adjust itself to a considerable extent to variations in the space across which it is interposed and so that the sealing member can be adjusted 65 as to its position whenever this may seem 70 desirable. Still further and also more detailed objects will appear from the following specification and from the accompanying drawings, in which—

Fig. 1 is an elevation of a refrigerator 75 door equipped with the sealing arrangement embodying my invention, taken from the inner side of the door.

Fig. 2 is a fragmentary enlarged view of 80 a corner portion of the same.

Fig. 3 is a correspondingly enlarged horizontal section through an edge of the door and through the adjacent portion of the casting of the refrigerator, taken with the door 85 in its closed position.

Fig. 4 is an enlarged portion of Fig. 3, showing the sealing strip as it appears when the door is still more tightly pressed shut.

Fig. 5 is a fragmentary section similar to 90 a portion of Fig. 4 showing the sealing member in two positions of adjustment.

Fig. 6 is a perspective view of a portion 95 of the sealing strip.

In accomplishing the purposes of my invention after the manner of the accompanying drawings, I construct the door of the refrigerator with a wooden rim 1 of such a size as to loosely enter within the inner frame portion 2 of the front of the refrigerator, this frame portion being here 100 shown as screwed to a corner post 3. The corner post itself is shown as partly surrounded by the outer metal side piece 4 of the refrigerator, while the frame portion 2 has screwed to it the inner metal shell portion 5 which forms part of the interior of the refrigerating chamber. The space between 105 the inner and outer metal sides 4 and 5 is filled with an insulating packing 6 of cork board or the like, and a similar heat-insu- 110

lating packing is interposed between the outer metal face 7 of the door and the inner metal face 8 of the door.

Extending around the inner edge of the door is a substantially endless and angle-sectioned rubber band having one web 9 bearing flatwise against the inner face of the door while its other web 10 is disposed for edgewise engagement with that portion 10 of the inner lining 5 of the refrigerating chamber which extends parallel to the face of the door and which is screwed to the frame member 2. The lining 5 and frame member 2 conjointly form an angular seat 15 11^a with which the web 10 engages. Thus arranged, the said portion 11 of the inner lining 5 also constitutes a forwardly facing ledge on the frame of the door, and by spacing this ledge from the inner face of the door by a distance less than the width of the web 10 of the sealing member, I cause this web to be compressed when the door is closed. To permit such a compressing action to flex the sealing member to an extent which will automatically compensate for the differences in distance between the parts in case the inner face of the door is not exactly parallel at all points with the forward face of the said ledge 11, I provide the rim or peripheral edge portion 1 of the door with a recess 12 which is overhung by the back of the web 10 of the sealing member, so that this back can be flexed into the said recess after the manner 35 shown in Fig. 4.

To hold the sealing member properly in position, I provide a series of metal clamping strips 13 fastened to the door strips 1 by screws 14. These strips, which desirably 40 are of a socalled half-oval cross-section, lap over the inner face of the web 9 of the sealing strip and clamp this web tightly against the inner face of the door. By starting with a suitable length of the sealing strip, 45 I can run this entirely around the inner edge of the door and can make the gap 15 between the ends of the strip so small as to be negligible. In other words, I can cause the sealing strip to afford a substantially 50 endless rubber band which extends entirely around the inner edge of the door and which presents an annular web extending inwardly from the door against the said ledge on the door frame.

With the parts properly proportioned, and with the web 10 of such a width that it will engage the said ledge 11 before the overhanging portion 16 of the metal door front engages the metal front lining 4 of the door frame; I can readily cause the sealing strip to engage the ledge 11 as shown in Fig. 3 even when the door is only lightly pressed shut. Then if the pressure is greater at any point along the sealing strip, the 60 sealing strip may be expanded in thickness 65

and also forced back into the recess 12 as shown in Fig. 4. In practice, the extent of this compression and distorting of the sealing member may vary considerably at different points of that member, thereby 70 compensating for irregularities in the shape and spacing of the door and door frame.

If the sealing member thus employed were permanently clamped in position, I might encounter the same objection which has been met with flat sealing strips heretofore tried for a similar purpose, namely, that the strip will wrinkle and hence will not afford the desired tight closure. To avoid this, I do not fasten the sealing strip by nails or screws 75 extending through it, but merely clamp it under a portion of the clamping strips 13 which in turn are secured in place by screws 14 that do not extend through the rubber sealing strip. In affixing the sealing strip, I 80 can initially tension this somewhat so as to stretch it around the outer edge of the clamping strips 13, whereupon the tensioned rubber strip will avoid any initial tendency 85 towards wrinkling. Furthermore, if gradual changes in the relative disposition of the door with respect to the door frame or any gradual change in the shape of the sealing strip reduce the initial sealing effect, I can readily readjust the sealing member by 90 merely loosening the screws 14 and sliding the web 9 of the sealing strip laterally after the manner shown in Fig. 5. That is to say, I can readily increase or decrease the 95 effective length of the angle-sectioned endless rubber band which constitutes my sealing strip. So also, this sealing strip can readily be removed and replaced if desired 100 by simply loosening the screws 14.

It will be obvious from the above that my entire arrangement is exceedingly simple, that the sealing means employed will readily adjust themselves to such variations as ordinarily might occur at various portions of the door, and that a further general adjustment also can readily be made if desired. Incidentally, my sealing strip through its cushioning action also avoids any slamming noise when the door is closed, thereby 110 accomplishing a further and highly desirable effect.

However, while I have illustrated and described my invention as applied to a refrigerator door and body of a particular construction, namely one having inner and outer metal linings, I do not wish to be limited to the use of my invention in connection with any particular type of refrigerator door. Nor do I wish to be limited to its use in connection with refrigerators, as it obviously 120 might be employed also in connection with other doors when a sealing of the same is desired. Neither do I wish to be limited to the details of the construction and arrangement herewith disclosed, as many 125 130

modifications might obviously be made without departing either from the spirit of my invention or from the appended claims, and particularly so since I have exaggerated the spacing of some of the parts in the drawings so as to make these show the underlying principles more clearly.

I claim as my invention:

1. In combination with a door frame, and a door having a continuous recess adjacent to the inner edges thereof, a compressible sealing member of substantially L-shape cross-section having one web thereof secured to the inner face of the door so as to cause the other web to lie in alinement with the recess and to have edgewise engagement with the door frame, whereby upon such engagement the apex portions of the member may move into the recess.
2. In combination with a door frame, and a door having a continuous recess adjacent to the inner edges thereof, a compressible sealing member of substantially L-shape cross-section having one web thereof secured to the inner face of the door so as to cause the other web to lie in alinement with the recess and to have edgewise engagement with the door frame, whereby upon such engagement the apex portions of the member may move into the recess, and clamping means for the first named web formed to permit the latter to be adjusted inwardly and outwardly relative to the inner edges of the door.
3. In combination with a door frame, and a door having a continuous recess adjacent to the inner edges thereof, compressible sealing means having a part thereof secured to the inner face of the door and having

a second part at an angle to the first named part and in register with the recess and having a free edge adapted for edgewise engagement with the door frame, whereby upon such engagement the second part may move into the recess in a plane at substantially right angles to the plane of the first named part.

4. In combination with a door frame having an angular seat at its inner edge, and a door having a recess in alinement with the seat, compressible sealing means secured to the door and having a part engaged in the angular seat and movable into the recess upon closing of the door, and means for securing the sealing means to the door so as to enable the sealing means to be moved inwardly or outwardly thereby to regulate the degree of engagement of the sealing means with the seat.

5. In combination with a door frame having an angular seat at its inner edge, and a door having a recess in alinement with the seat, a compressible sealing means of L-shape cross section having one web secured to the inner face of the door and having a second web formed to engage in the angle of the seat whereby upon such engagement the apex portion of the sealing means may move into the recess, and means for securing the sealing means to the door so as to enable the sealing means to be moved inwardly or outwardly thereby to regulate the degree of engagement of the second web with the angular seat.

Signed at Chicago, Illinois, May 25th, 1923.

JOHN TWARDOWSKY.
